ATTORNEY

UNITED STATES PATENT OFFICE.

GEORGE F. IRELAND, OF FORT TOTTEN, NEW YORK.

PENCIL-CUSHION.

No. 902,238.

Specification of Letters Patent.

Patented Oct. 27, 1908.

Application filed August 17, 1906. Serial No. 330,948.

To all whom it may concern:

Be it known that I, GEORGE F. IRELAND, a citizen of the United States of America, and resident of Fort Totten, in the county of 5 Westchester and State of New York, have invented certain new and useful Improvements in Pencil-Cushions, of which the following is a specification.

My invention relates to a household or 10 business article for holding a plurality of pens, pencils or similar articles, canes, umbrellas or similar articles, incandescent electric lamps, or other objects to which the device is adapted.

15 The special objects of the invention are to provide a holder which is as easily used for pens and pencils as a pin cushion is for pins and needles.

Without regard to the exact scope of the 20 invention which is attended to in the claims, the organization embraces a rubber base, a concavo-convex rubber piece thereon and integral therewith, and having a plurality of parallel perforations therethrough, the lower 25 portions of which are cylindrical, and the upper portions taperingly hexagonal.

Figure 1 is a plan of the article. Some of the holes are shown circular, but they may all be of the shape seen in Fig. 3, on an enlarged scale. Fig. 2 is a side elevation, with some omissions, and with some hidden parts shown in dotted lines. Fig. 3 is plan of a portion of a similar article, with the perforations therein of preferred form, and shown 35 on a greatly enlarged scale, the article in the former figures being about the natural size. Fig. 4 is a vertical section centrally through the rubber to exhibit the approximate shape internally. Fig. 5 is a plan of a holder so 40 changed as to be adapted to hold a square ink bottle.

The article as shown in Figs. 1 and 2 consists of the base *a*, on which is a concavo-convex piece *b*, integral with the base, with the 45 concave portion toward the base, by which the article is partly hollow, as indicated by the dotted line *c*, and having numerous perforations *d*, *e*, *f*, *g*, *h*, *i*, *j*, etc.

When circular holes are employed as 50 shown in Figs. 1 and 2, there are comparatively large triangular portions between the

holes, even when the latter are as close together as practicable. When the pen or pencil is therefore darted into the article, it is almost as likely to strike the rubber as a hole, 55 whereas I desire it to be as sure to enter a hole as a pin is to puncture a pin cushion.

According to the scope of invention shown in Figs. 1, 3 and 4, this favorable result may be accomplished. The lower portions of the 60 holes still remain cylindrical, but the upper portions are gradually enlarged and developed into the shape of truncated hexagons, *k*, with the consequence that thin walls *l* with equal thickness throughout the upper edges, 65 and flexible and easily yielding are produced, said walls forming hexagonal partitions, the same as in a honey comb.

In the ink-stand shown in Fig. 5, there is a 70 base *A*, on which there are two pieces *B* having cylindrical hexagonal holes therein, and spaced sufficiently apart to leave room at *M* for an ink bottle. There are vertical walls *N* connecting the pieces *B* for preventing the ink bottle from slipping out of the opening *M*. 75

The invention may be modified without departing from the spirit thereof. For example, that portion of the base *a* which is directly under the perforated piece *b* may be omitted. It is preferable however, be- 80 cause it prevents the point of a pen or the ink thereon, from damaging a table or desk.

I claim as my invention—

1. A holder consisting of a rubber base, and a concavo-convex rubber piece thereon, 85 having a plurality of perforations therethrough.

2. A holder consisting of a mass of rubber having a plurality of contiguous and parallel cylindrical perforations, with the upper portion of each perforation enlarged to form a hexagonal opening, so that the wall between any of the central perforations and the six next adjacent perforations is hexagonal both on the inside and on the outside. 95

In testimony that I claim the foregoing as my own, I have hereto affixed my signature in the presence of two witnesses.

GEORGE F. IRELAND. [L. S.]
